(57) **CLAIM**

The ornamental design for a toy football table, as shown and described.

DESCRIPTION

FIG. 1 is a perspective view of a toy football table showing my new design;

FIG. 2 is a right side elevational view thereof;

FIG. 3 is a top plan view thereof;

FIG. 4 is a front elevational view thereof;

FIG. 5 is a bottom plan view thereof;

FIG. 6 is a left side elevational view thereof; and,

FIG. 7 is a rear elevational view; and,

FIG. 8 is a perspective view of the toy football table with legs.

The broken line showing of legs in FIG. 8 is for illustrative purposes only and forms no part of the claimed design.
